AURORA AUTOMATIC MACHINERY COMPANY, OF CHICAGO, ILLINOIS, A CORPORA-
TION OF DELAWARE.

RIVET-SET RETAINER.

1,405,669.

Specification of Letters Patent. Patented Aug. 4, 1914.

Application filed January 7, 1914. Serial No. 810,717.

To all whom it may concern:

Be it known that we, AXEL LEVEDAHL and REINHOLD A. NORLING, citizens of the United States, and residents of Aurora, in the county of Kane and State of Illinois, have invented certain new and useful Improvements in Rivet-Set Retainers; and we do hereby declare that the following is a full, clear, and exact description thereof, reference being had to the accompanying drawings, and to the letters of reference marked thereon, which form a part of this specification.

This invention relates to a rivet set retainer adapted for maintaining a rivet set in operative position upon the end of the barrel of a riveting hammer or like tool, in a manner to prevent the dislodgment thereof under the impact of the plunger of the hammer.

A retainer embodying our invention is so constructed as to have a detachable connection with the hammer-barrel, so that the retainer may be easily and quickly removed from such barrel, and also has detachable connection with the rivet set, so that the rivet set may be readily removed from the same and from the end of the barrel and another set substituted for the one removed, without removing the retainer from the barrel. The retainer being connected with the barrel when the rivet set is removed, the retainer will not become displaced or lost, but will always be in position on the barrel to receive a rivet set. The retainer is movably mounted on the barrel and its movement in both directions cushioned by springs or yielding means. By reason of this fact, any blow or shock that the retainer may receive through the action of the hammer plunger on the set will be absorbed by the yielding means interposed between the retainer and the barrel and such blow or shock will not be imparted to nor do injury to the barrel, nor will it break or injure the retainer. The retainer is designed to accommodate rivet sets having working faces of various sizes and the use of the same is not confined to a special set or a standard set. The retainer will receive the largest kind of rivet set.

The invention consists in the matters hereinafter described and more particularly pointed out in the appended claims.

In the accompanying drawings—Figure

1 is a side view of a pneumatic hammer and rivet set applied thereto and showing in axial section a rivet set retainer made in accordance with our invention and applied on the barrel of said hammer and engaging said rivet set; Fig. 2 is an enlarged side elevational view of the retainer, the same being shown as applied upon the tool barrel and engaging the said rivet set; only fragments of the barrel and set being shown; Fig. 3 is a sectional view of the retainer taken on line 3—3 of Fig. 4; Fig. 4 is an end view of the retainer, the parts thereof being interlocked but removed from the tool barrel; Fig. 5 is a view in side elevation of the retainer showing the two sections or parts thereof in one position they assume when the same are being applied to the barrel; Fig. 6 is a view in side elevation of the same parts shown in Fig. 5, one of the two sections of the retainer being shown in the position it occupies just prior to being thrust forward to be interlocked with the other section. Fig. 7 is a sectional view taken on line 7—7 of Fig. 6; and Fig. 8 is a view in side elevation showing the retainer on the barrel and with the two sections thereof in position with their forward ends separated or opened to permit the rivet set to be inserted into the nozzle of the barrel or to be removed therefrom.

Referring to the drawings, illustrating in detail a rivet set retainer constructed in accordance with the present invention, said retainer is shown as slidably mounted upon the barrel 10 of a riveting tool, and is adapted to hold upon the forward end of said barrel, a rivet set 11, which is so engaged with the barrel as to permit endwise movement of the set relatively to the barrel. The riveting tool shown is of the pneumatic type and the barrel 10 is provided with a handle 10^a as usual in tools of this character. (See Fig. 1). The barrel 10 is provided adjacent its forward or nozzle end with two longitudinally spaced projections, 12, 13, preferably in the form of annular ribs forming annular shoulders which face toward each other and between which are located two helical springs 14, 15 encircling the barrel and bearing against said shoulders 12, 13, respectively. The spring 14 is the heavier or stronger of the two and bears against the shoulder 12 next adjacent to the nozzle end of the barrel. The spring 15 bears against

the other shoulder 13 and both springs normally expand toward each other. As shown in Fig. 1, the outer surface of the forward or nozzle end of the barrel is tapered or conical and the springs are pressed over the tapered or conical end of the barrel in placing them on said barrel.

The rivet set 11 is provided with a shank or stem 16 adapted to be inserted into the bore 10^b of the barrel from the nozzle end of the barrel. The hammer plunger (not shown) operates against the inner end of said shank 16, within the bore of the barrel, as customary in tools of this character. To limit the distance the shank 16 is inserted into the bore 10^b, said rivet set 11 is provided with an integral, outwardly projecting, annular flange 17, forming a stop surface or shoulder adapted to abut against the end face of the barrel, as shown in Fig. 1.

For holding the rivet set 11 in place on the barrel, while permitting the necessary endwise movement of the set relatively to the barrel, a retainer 18 is provided; the same being constructed as follows: The retainer 18, as shown in the drawings, is in the form of a two-part tubular member or sleeve open at both ends and adapted to be placed over the nozzle end of the barrel 10, with one end of the retainer projecting beyond the end of the barrel. (See Fig. 1). The outer end portion of the retainer 18, which projects beyond the end of the barrel 10, is preferably conical and projects over and incloses or embraces flange 17 and adjacent part of the rivet set 11, when the latter is on the end of the barrel. The remaining or body portion of said retainer 18 is preferably cylindrical and extends rearwardly over, while being spaced outwardly from the barrel, and incloses or surrounds the spring 14. The retainer 18 is provided at its outer end and at a distance from the end of the barrel, with an annular flange 19 extending inwardly toward the rivet set 11 beyond or exterior to flange 17. As shown, said flange 19 extends into the annular groove 21 formed between the flange 17 and an inwardly facing shoulder 20, formed by reducing the diameter of the portion of said rivet set between said parts. Said retainer 18 is provided at its opposite or rear end with an annular, inwardly extending flange 22 which is inserted between the opposed ends of the heavy and light springs 14, 15, respectively. These springs expanding endwise toward said flange 22 act to hold the flange 22 and the retainer 18 yieldingly in one position. The flange 22 extends into the space between said shoulders 12, 13 and said flange 22 is adapted to slidably engage the surface of the barrel between said shoulders. The springs 14, 15 provide a yielding connection acting to hold the retainer 18 yieldingly from endwise movement on the barrel 10,

and normally in such position that the flange 19 at the outer end of the retainer is adjacent to or in contact with the shoulder 20 on the set 11. Should the flange 17 on the set be forced into contact with the flange 19 of the retainer, under a blow of the hammer plunger, the force of the blow or shock on the retainer will be resisted and absorbed by the spring 14 against which said retainer 18 would be forced under such blow. In other words, the spring 14 acts to cushion the movement of the retainer when suddenly moved forward by the impact of the rivet set on the retainer. The other spring 15 cushions the movement of the retainer in the opposite direction and serves to absorb the recoil of the heavy spring 14 after a blow has been imparted to the retainer. By yieldingly mounting the retainer on the barrel, any blow or shock which the retainer receives is absorbed by the springs and is not imparted to the barrel. Moreover, by reason of the yielding connection of the retainer with the barrel, such retainer will not be damaged or injured by the impact of the set against the same.

In order that the retainer 18 may be readily placed on and taken off of the barrel 10, and further in order that the rivet set 11 may be detachably maintained in position upon the end of the barrel by the retainer, so that the rivet set may be removed from the barrel and another set substituted for the one removed without removing the retainer from the barrel, the retainer is divided longitudinally into two sections 23, 24, each section preferably forming a half of the retainer and being provided with means by which they have interlocking connection with each other at their lateral meeting edges. Each section 23, 24, is provided with half of each flange 19 and 22, respectively. The interlocking connection for the sections is made as follows: One of the halves or sections, preferably the one 23, is provided at its lateral edges with a flange 25, 25, extending the full length of the section and bent to form inwardly facing, longitudinal channels, adapted to receive the outwardly extending, longitudinal sets or flanges 26, 26 on the like edges of the other section 24. (See Figs. 2 and 3). As shown, each flange 25, 25 is integral with the section 23 and hook-shaped in cross-section. (See Fig. 4). Each flange 26, 26, on the section 24 is preferably integral with the said section. Each hook-shaped flange 25, 25 is provided near its end adjacent the end of the section at which the flange 22 is located, with a slot 27, 27 opening through the margin of the flange 25, 25, and into the longitudinal channel formed thereby. The outer end portion of the retainer 18, adjacent the flange 19, being conical, it follows that the similar portions of each section 23, 24 are likewise

conical. The forward edge 26^a of each flange 26, 26, terminates short of the conical portion of the section 23, and each flange 26 is continued along the conical portion of said section. In other words, the flange 26, 26 at and adjacent the conical portion of the section 24 is cut away and the inner edge 26^b of the flange on the conical portion terminates in alignment with and forms a continuation of the cylindrical surface of the body of the section 24. (See Fig. 7). The length of each portion of the flange 26, 26 on the cylindrical or body part of the section 24 is greater than the distance between the inner end of the hook-shaped flange 25 and the forward edge 27^a of the slot 27. (See Figs. 2 and 3.)

The retainer 18 is applied upon the barrel 10 in the following manner: The section or half 23 is placed in position over the forward end of the barrel with the flange 22 thereof inserted between the opposed ends of the springs 14 and 15, as shown in Fig. 5. Said section 23 is held in this position by the hand of the operator. The other section 24 is then placed over the end of the barrel 10 with the inner end portions of the flanges 26, 26 inserted through the slots 27, 27 in the flanges 25, 25 on the said section 23. (See Fig. 5). The section 24 is then moved endwise of the barrel toward the handle 10^a until its flange 22 is in position for inserting between the opposed ends of the springs 14, 15. The section 24 is then pushed toward the handle 10^a until the forward edge 26^a of each flange 26, 26, passes the forward end 27^a of the slot 27, 27, whereupon the section 24 is moved laterally toward the other section 23 and portions of the flange 26, 26 on the cylindric or body part of the section 24 will be brought within the channels formed by said flanges 25, 25. (See Figs. 6 and 7). The spring 15 is compressed in the movement of the section 24 toward the handle 10^a, as shown in said Figs. 6 and 7, and when the section 24 is released, the said section 24 will be thrust forward by the expansion of the spring 15 and the forward end 26^a of each flange 26, 26, moved into the channel formed by the flanges 25, beyond the edge 27^a of the slots 27, 27. (See Figs. 2 and 3). The sections 23, 24 when interlocked together inclose or surround the forward end of the barrel 10 and constitute the rivet set retainer 18. When the section 24 is in the position shown in Figs. 6 and 7, the forward edge 26^a of each flange 26 is rearward of the forward edge 27^a of each slot 27, 27 and the forward flange 19 of the section 24 is to the rear of the like flange of the section 23. In this position of the parts the flanges 26, 26, on the conical portion of the section 24 are in registration with the channels formed by portions of the flanges 25, 25 on the conical portion of the

section 23. Manifestly, when the section 24 is moved forward by the action of the spring 15, the flanges 26, 26 on the conical portion of the section 24 will enter the channels formed by the flanges 25, 25 on the conical portion of the section 23. It follows, that not only the cylindric portions, but also the conical parts of the sections 23, 24 become interlocked. To allow the flanges 26, 26 to pass readily through the slots 27, 27, the channels formed by said flanges 26, 26, are widened at their rear ends by bending each end portion 25^a of each flange 25, 25 laterally outward while the outer marginal face 29, 29 of each flange 25, 25, at and adjacent the forward end of each slot 27, 27 is beveled or inclined inwardly. To remove the retainer from the barrel 10, the section 24 is moved rearwardly against and compressing the spring 15 until the outer ends 26^a, 26^a of the flanges 26, 26 have passed the forward edges 27^a, 27^a of the slots 27, 27, whereupon the section 24 may be moved laterally away from the section 23, when the flanges 26, 26, under the expansive action of the spring 15, are moved outwardly through the slots 27, 27. Then the section 24 may be separated from the other section 23 and the two sections removed from the barrel 10.

To apply a rivet set, when the retainer 18 is on the barrel 10, without removing the retainer 18 from the barrel, the section 24 is pushed back or toward the handle 10^a against the spring 15 until the outer end 26^a of each flange 26 on said section is in position to pass through the slots 27, 27, whereupon the section 24 is moved laterally away from the section 23 and the flanges 26, 26 allowed to pass through the slots 27, 27. The outer ends of the sections 23, 24 will then be separated, as shown in Fig. 8, so as to permit the shank 16 and flange 17 of the rivet set to pass therethrough in the insertion of the shank of the rivet set into the nozzle of the barrel. After the rivet set is in its operative position, the section 24 is pushed toward the handle 10^a against the spring 15 and the sections interlocked in the manner above described. When it is desired to remove the rivet set and substitute therefor another rivet set of the same or of a different kind, the sections 23, 24 are moved endwise relatively to each other and the outer ends thereof separated, as above described. The forward portions of the sections 23, 24 being conical and interlocked, the sections are prevented from endwise movement relatively to each other toward the nozzle end of the barrel. The spring 15 acting to bear against each of the sections when the sections are interlocked and in operative position serves to prevent endwise movement of the sections relatively to each other toward the handled end of the barrel,

or, in other words, in a direction to effect the disconnection of the interlocking parts of the sections. It follows that the spring 15 acts in effect as a lock and serves to yieldingly resist endwise movement of the sections when the conical end portions are separated to permit the application of or removal of a set.

A rivet set retainer constructed as above described is adapted for holding in operative position upon the end of the barrel of a pneumatic hammer or other riveting tool, rivet sets having working faces of varying sizes and the use of the same is not confined to any special set or to the standard set. The sets may be quickly and easily applied to or removed from the end of the barrel without removing the retainer from the barrel. Manifestly, a retainer made and applied as stated, will not become displaced or lost, is retained on the barrel when any rivet set is removed, and the retainer will always be in position on the end of the barrel to receive other rivet sets that it may be desired to use.

By reason of the two springs 14, 15 pressing against the flange 17 of the retainer, said retainer has endwise yielding connection with the barrel, and the retainer is cushioned or yieldingly held against movement in both directions. The springs practically eliminate any lateral vibration of the retainer, due to the riveting operation. The spring 14 will preferably be made heavy or strong enough to resist and absorb any shock or blow that the retainer may receive by the flange 17 on the set being suddenly forced against the forward flange 19 of the retainer, as might happen in case the rivet set is not held against the work, or if the tool should be started in operation when not in position to act on a rivet. By reason of the fact that any shock or blow the retainer may receive is absorbed by the springs, such a shock or blow will have no effect to break or injure either the retainer or the barrel. It is to be of course understood that the spring 14, which acts to cushion the retainer against the effect of the blows it may receive from the hammer plunger through the rivet set, will be made strong enough to arrest the outward movement of the set and retainer, before the coils of the said spring are brought into contact with each other in the outward movement of the set and retainer, such as would occur if the hammer were started in operation when the set is not in contact with the rivet. The second spring 15, in addition to preventing relative movement of the sections of the retainer with respect to each other, acts to absorb or take up the recoil of the heavy spring 14 after the latter has been compressed by a blow on the set, thereby obviating liability of the retainer being fractured or injured by impact

against the barrel in any backward movement or recoil of the retainer.

Although the retainer is shown in the accompanying drawings as applied to a riveting tool of the pneumatic type, yet it is to be understood that said retainer will be equally well applicable to riveting tools or hammers of the electrically operated type or to tools or hammers for like purposes operated by any other kind of motive power.

It is to be understood that the details of construction of the retainer illustrated may be variously modified without departing from the spirit of our invention, and we do not wish to be limited to the features of construction shown except as pointed out in the annexed claims.

We claim as our invention:

1. In combination with the barrel of a riveting tool, or the like, a rivet set, a retaining member having endwise movement relatively to said barrel and adapted to engage the rivet set, said retaining member comprising a plurality of longitudinal sections having parts adapted to interlock in the movement of said sections relatively to each other in one direction, and means applied to yieldingly resist the endwise movement of said retaining member relatively to said barrel.

2. In combination with the barrel of a riveting tool, or the like, a rivet set, a retaining member having endwise movement relatively to said barrel and adapted to engage the rivet set, and means applied to yieldingly resist both the outward and inward movement of said retaining member relatively to said barrel, embracing resilient members acting toward each other and against the opposite sides of a rigid part of said retaining member.

3. In combination with the barrel of a riveting tool, or the like, a rivet set, a retaining member having endwise movement relatively to said barrel and adapted to engage said rivet set, and means applied to yieldingly resist both the outward and inward movement of said retaining member relatively to said barrel, comprising two helical springs encircling said barrel and acting in opposite directions on said retaining member.

4. In combination with the barrel of a riveting tool, or the like, a rivet set, a retaining member having endwise movement relatively to said barrel and adapted to engage said rivet set, said barrel being provided with two longitudinally spaced, annular shoulders facing toward each other, two helical springs encircling said barrel between and bearing against said shoulders and acting in opposite directions on said retaining member.

5. In combination with the barrel of a riveting tool, or the like, a rivet set, and a

retaining member comprising a plurality of longitudinal sections applied to said barrel and adapted to engage said rivet set, said sections having parts adapted to interlock in the movement of said sections relatively to each other in one direction.

6. In combination with the barrel of a riveting tool, or the like, a rivet set, a retaining member having endwise movement relatively to said barrel and comprising a plurality of longitudinal sections adapted to engage said rivet set, said sections having parts adapted to interlock in the movement of said sections relatively to each other, and means applied to yieldingly resist both the outward and inward movement of said retaining member relatively to said barrel.

7. In combination with the barrel of a riveting tool, or the like, a rivet set, a retaining member having endwise movement relatively to said barrel and comprising a plurality of longitudinal sections adapted to engage the rivet set, said sections having parts adapted to interlock in the movement of said sections relatively to each other in one direction, and means applied to yieldingly engage said sections and resist the relative movement of said sections in a direction to effect the disconnection of said interlocking parts.

8. In combination with the barrel of a riveting tool, or the like, a tubular retaining member having endwise movement relatively to said barrel and adapted to engage the rivet set, and means applied to yieldingly resist the endwise movement of said member relatively to the barrel, embracing two helical springs acting toward each other and against the opposite sides of an annular flange on said retaining member.

9. In combination with the barrel of a riveting tool, or the like, a rivet set, and a tubular retaining member having endwise movement relatively to said barrel and comprising a plurality of longitudinal sections the lateral edges of which are provided with parts adapted to interlock in the movement of said sections relatively to each other in one direction, each of said sections being provided at each end of the retainer with an inwardly directed flange, the flange at the forward end of the retainer being adapted for engagement with said rivet set, and resilient means applied to engage the flange at the rear end of the retainer for yieldingly resisting the endwise movement of the retainer relatively to said barrel.

10. In combination with the barrel of a riveting tool, or the like, a rivet set, and a tubular retaining member applied to said barrel and comprising at least two longitudinal, detachably connected sections adapted to engage said rivet set, one of said sections being provided with lateral

flanges shaped to form inwardly facing, longitudinal channels, and the other of said sections being provided with lateral ribs adapted to be received by said channels, for effecting the connection of said sections.

11. In combination with the barrel of a riveting tool, or the like, a rivet set, and a tubular retaining member applied to said barrel and comprising at least two longitudinal, detachably connected sections adapted to engage said rivet set, each of said sections forming a longitudinal portion of the retainer, one of said sections being provided with lateral flanges shaped to form inwardly facing, longitudinal channels, the other of said sections being provided with lateral ribs adapted to be received by said channels; said flanges being provided intermediate their ends with marginal, inwardly opening slots through which said ribs are adapted to pass when brought into said channels, for effecting the connection of said sections.

12. In combination with the barrel of a riveting tool, or the like, a rivet set, and a tubular retaining member applied to said barrel and comprising at least two longitudinal sections adapted to engage said rivet set, each of said sections forming a longitudinal portion of the retainer, one of said sections being provided with lateral flanges shaped to form inwardly facing, longitudinal channels; the other of said sections being provided with lateral ribs adapted to be received by said channels, said flanges being provided intermediate their ends with marginal, inwardly opening slots through which are adapted to pass the ribs when the latter are brought into said channels, said ribs terminating short of the forward end of the section of which they form a part and adapted to bridge and overlap the forward edges of said slots when said ribs are in operative position in said channels.

13. In combination with the barrel of a riveting tool, or the like, a rivet set, a retaining member having endwise movement relatively to said barrel and comprising a plurality of longitudinal sections adapted to engage said rivet set; one of said sections being provided with lateral flanges shaped to form inwardly facing, longitudinal channels, and the other of said sections being provided with lateral ribs adapted to be received by said channels, for effecting the connection of said sections, and means applied to yieldingly resist the endwise movement of said retainer relatively to said barrel.

14. In combination with the barrel of a riveting tool, or the like, a rivet set, a retaining member having endwise movement relatively to said barrel and comprising a plurality of longitudinal sections adapted to engage said rivet set; one of said sections

being provided with lateral flanges adapted to form inwardly facing, longitudinal channels, and the other of said sections being provided with lateral ribs adapted to be received by said channels, said flanges being provided intermediate their ends with marginal, inwardly opening slots through which said ribs are adapted to pass when brought into said channels, for effecting the connection of said sections, and means applied to yieldingly resist the endwise movement of said retainer relatively to said barrel.

13. In combination with the barrel of a riveting tool, or the like, a rivet set, a retaining member having endwise movement relatively to said barrel and comprising a plurality of longitudinal sections adapted to engage said rivet set; one of said sections being provided with lateral flanges shaped

to form inwardly facing, longitudinal channels, and the other of said sections being provided with lateral ribs adapted to be received by said channels, for effecting the connection of said sections, and means applied to yieldingly resist the endwise movement of said sections relatively to said barrel embracing two helical springs acting toward each other and against the opposite sides of a flange on each of said sections.

In testimony, that we claim the foregoing as our invention we affix our signatures in the presence of two witnesses, this 23rd day of December A. D. 1913.
